UNITED STATES PATENT OFFICE.

HENRY J. MONTY, OF LOWELL, MASSACHUSETTS.

TWO-SECTION PICKER.

Application filed October 18, 1927. Serial No. 226,979.

This invention relates to a picker mechanism employed in the formation of a lap suitable for passage to a carding or other similar process from wool, cotton or other fibre:

The object of the invention is to provide a picker mechanism which shall be compact, occupying a minimum amount of space, which shall reduce the number of picking operations necessary to produce a high grade lap, and which shall produce a lap having a uniform weight per unit length.

The object of the invention is further to provide a two-section picker in which the lap is passed directly from the first section to the second section with the continuity of the lap maintained, with the lap under proper tension, and with the lap delivered to the second section with a substantially constant weight per unit length.

These and other objects of the invention will appear more fully from the accompanying description and drawings and will be particularly pointed out in the claims.

As the invention has to do only with the handling of the lap in its passage between the two sections of a two-section picker and as picker mechanisms of various forms with their driving connections are well known and familiar to those skilled in the art, it will be sufficient to employ herein a diagrammatic illustration of an ordinary type of picker mechanism while illustrating more in detail the new parts selected as a simple and preferred embodiment of the present invention.

In the drawings:

Fig. 1 is a diagrammatic view of a picker mechanism including an automatic feeder, an opener or breaker picker, an intermediate picker, a finishing picker, the latter two constituting the two-section picker with which the invention is particularly concerned, and a mechanism embodying the invention.

Fig. 2 is a top plan view of certain elements directly concerned with the taking up of slack in the lap.

Fig. 3 is a side elevation, with some of the usual driving connections and other familiar parts omitted, showing an evener mechanism and slack-controlling mechanism embodying a preferred form of the invention.

Fig. 4 is a detail of another form of the slack-controlling feature.

The invention may be employed in connection with various forms of picking mechanism. In Fig. 1 there is shown a mechanism comprising an automatic feeder 1, an opener or breaker picker 2, an intermediate picker 3 and a finishing picker 4. Each of these sections will be recognized from the diagrammatic view as of a familiar type. The fibre such as cotton or wool is placed in the automatic feeder 1 and discharged therefrom on to the feeding apron 5 of the opener or breaker picker section 2. From this apron it passes under the control of a familiar type of evener mechanism 6 to the breaker 7, shown as of the porcupine type, where it is broken up and thence delivered to the cages 8 where it is passed through the feeding rolls 9 in the form of a loose lap. This loose lap then passes to the intermediate picker section 3. It enters this section through the feed rolls 10, is broken up by the breaker 11 and thence passed to the cages 12 and from these is again taken in the form of a loose lap. The finishing picker 4 receives the fibre from the breaker 13, passes it to the cages 14 and delivers it in the form of a loose lap through the feed rolls 15 to the usual lap forming mechanism 16 where it is compressed and wound up ready for carding or other subsequent operations.

It is highly important that the finished lap shall be uniform throughout and present, so far as possible, a constant, uniform weight per unit length so that every square yard, for example, shall be of the same weight and have the fibre uniformly distributed throughout.

It will be seen that the only mechanism employed for controlling the character and weight of the lap thus far mentioned is the evener mechanism 6 which acts upon the fibre as it enters the breaker picker 2. But the fibre at this stage is only partially opened up and separated and is very unevenly distributed, so that the lap discharged from the intermediate picker 3 is still far from uniform in its character.

Heretofore the common practice has been to introduce an opener between the intermediate picker and the finishing picker,

which acts to destroy the lap between these sections.

In this invention the continuity of the lap is preserved in its passage from the intermediate to the finishing picker or between the sections of a two-section picker, and this lap is introduced to the finishing picker or the second section in its lap form. In this invention the thickness of the lap throughout its width as it passes to the second or finishing picker section is controlled to maintain constant, so far as possible, the amount fed per unit length to this second section. This means that there will be more or less slack in the lap in its passage between the two sections which, by reason of the soft, loose character of the lap, would result in its breaking apart or otherwise losing its continuity. The invention therefore provides for the taking up of such slack in the lap, thus maintaining the continuity of the lap and preserving the proper tension on the lap.

The invention, in the preferred form illustrated, therefore provides between the two sections of a two-section figure, as between the intermediate picker 3 and the finishing picker 4, an evener mechanism and a slack-controlling mechanism, with the slack-controlling mechanism preferably under the control of the evener mechanism. At the discharge end of the first section of the two sections under consideration, namely, at the discharge end of the intermediate picker 3, the lap passes between feed rolls 17 and 18. From thence it passes over the slack-controlling element, under a guide roll 19, on to a feed apron 20 and thence from this feed apron between a feed roll 21 and operating evener shoes 22, and from thence into the breaker 13 of the second picker section, in this case the finishing picker 4. The feed roll 21 and the apron 20 are driven together and the speed thereof is controlled by an evener mechanism herein shown as of a generally familiar type and illustrated more in detail in Fig. 3. The slack-controlling element 23 is a vertically movable support which may take different forms, two of which are illustrated in Figs. 1 and 4 and in Figs. 2 and 3, respectively, but in either case, in the preferred form of the invention, the vertical movement of this support is controlled by the evener mechanism so that the slack in the lap is taken up by a vertical movement of this support in coordination with the speed of the feed roll 21 and feeding apron 20.

Referring now to Fig. 3, there is shown sufficient of an evener mechanism of a generally familiar type to make clear the additions and modifications suitable for an embodiment of the present invention. The feed roll 21 and feeding apron 20 are driven at the same surface speed by connections, not

shown, from the shaft 24. This shaft is shown as provided with a cone pulley 25 driven by a belt 26 from the opposed cone pulley 27 on a suitable driven shaft 28 extending at one side of the machine. The evener shoes 22, which extend across the picker beneath the feed roll 21 in the usual manner, form the shorter arms of a series of levers 290 fulcrumed at 29. The resultant movements of these levers is transmitted through the usual connections 30 to raise or lower the lever 31 in accordance with the average thickness of the lap passing between the feed roll 21 and the row of shoes 22. The movement of the lever 31 is transmitted by the link 32 adjustably connected to the arm 33 of the bell crank lever fulcrumed at 34 and having its other arm 35 presenting a gear segment 36 engaging teeth on the underside of a rack bar 37 mounted for horizontal movement. This rack bar 37 carries an arm 38 embracing the belt 26. All of this mechanism specifically considered is of a familiar type and it will be seen that according as the average thickness of the lap passing between the feed roller 21 and the shoes 22 increases or decreases as compared with the desired normal thickness, the belt 26 is shifted correspondingly to decrease or increase the speed of the feed roll 21 and the feeding apron 20 and thus acts to maintain constant the weight per unit length of the lamp being fed past the feed roll 21.

To this mechanism is added, in the construction shown in Figs. 2 and 3, a shaft 39 extending transversely of the picker. This shaft has secured thereto a gear 40 meshing with teeth on the upper side of the rack bar 37 and also has secured thereto pinions 41 meshing with rack bars 42 mounted for vertical movement one at each side of the machine. These rack bars which thus move in unison have journalled therein at their upper ends the roll 43 which extends across and beneath the lap about midway between the feed rolls 17 and 18, discharging the lap from the first picker section and the guide roll 19 and rear end of the apron 20 which take the lap and pass it on to the second picker section. It will thus be seen that the vertical movement of the supporting roll 43 is effected by and depends upon the movement of the rack bar 37 and consequently is controlled by the thickness of the lap passing the feed roll 21. The construction is so arranged that any slack in the lap after it is discharged from the first picker section by the feeding rolls 17 and 18 is taken up by the requisite bodily vertical movement of the roll 43. In the preferred construction illustrated, this vertical movement is under the control of the evener mechanism. Consequently an increase in thickness of the lap passing the feed roll 21 which will produce slack in the lap re-

sults in a vertical movement of the roll 43 sufficient to take up this slack. The speed of the entire picking mechanism is so adjusted that the feeding roll 21 and feeding 5 apron 20 will not take more lap than is delivered by the feed rolls 17 and 18 so that the vertical movement of the supporting roll 43 takes place between the point where its top surface is in line with the top surface of 10 the feeding apron 20 of the roll 18 and a point vertical thereabove sufficient to take care of the maximum slack in the lap. In Fig. 3 this roll is shown at a mid or normal position.

15 It is desirable that the surface of the support for taking up the slack such as the roll 43 shall move with the lap and consequently the roll 43 is shown as freely revoluble on its journals. But it may also be 20 desirable under some circumstances to have the supporting surface positively driven to cause it to travel with the lap. A construction for this purpose is shown in Figs. 1 and 4 wherein the rack bars 42 have journalled 25 therein, instead of the single roll 43, a pair of vertically spaced rolls 44 and 45 extending across and beneath the lap with an endless apron 46 on said rolls. This apron is positively driven so as to have substantially 30 the same surface speed as that of the lap and thus travel forward with the lap. The drive of the apron may be secured in any suitable way, as, for example, by a belt 47 running over pulleys of the same size on the 35 feed roll shaft 18 and the shaft of the roll 45. A suitable tension idler 48 must be provided because of the bodily movement of the apron with respect to the roll 18.

40 The travel of the fibre through the apparatus is indicated by the arrows in Fig. 1 and a portion of its path of travel at the place where the slack occurs is indicated in dotted lines 49 in Fig. 3 and again in full lines at 50 in Fig. 4.

45 Having thus described the invention, what is claimed as new, and desired to be secured by Letters Patent, is:

1. A picker comprising two-sections, an evener mechanism for the lap passing from 50 the first section to the second section and means for automatically taking up the slack in the lap between the first section and the evener mechanism, thereby to maintain constant the weight per unit length of the lap fed to the first section and to maintain the continuity of the lap under a proper tension in its passage from the first section to the evener mechanism.

2. A picker comprising two-sections, an 60 evener mechanism for the lap passing from the first section to the second section and means controlled by the evener mechanism for automatically taking up the slack in the lap between the first section and the evener mechanism, thereby to maintain constant

the weight per unit length of the lap fed to the second section and to maintain the continuity of the lap under a proper tension in its passage from the first section to the evener mechanism.

3. A picker comprising two-sections, an evener mechanism for the lap passing from the first section to the second section and means controlled by the thickness of the lap through out its width as it passes to the second section both for varying the feed of the lap to the second section to maintain constant the weight per unit length fed and for taking up any slack in the lap resulting from the variation in feed to maintain the continuity of the lap under proper tension.

4. A picker comprising two-sections, a feed roll at the entrance to the second section, evener shoes cooperating with the feed roll, a pair of feed rolls at the discharge end 85 of the first section, an endless feed apron for passing the lap from the discharging feed rolls of the first section to the cooperating feed roll and evener shoes, a guide roll above the rear end of the feed apron, a support extending across and beneath the lap between the discharging feed rolls of the first section and the rear end of said feed apron, and mechanism controlled by the evener shoes for simultaneously varying the speed of the feed roll and feeding apron and for moving the support vertically to maintain constant the weight of the lap per unit length fed to the second section and the continuity and tension of the lap between the discharging feed rolls 95 of the first section and the apron.

5. A picker comprising two-sections, means for feeding the lap from the first section, means for feeding the lap to the second section, an evener mechanism for the latter feeding means, a support extending across and beneath the lap between the two feeding means, and means for raising and lowering the support in coordination with each decrease and increase in the speed of the means for feeding the lap to the second section whereby a continuous lap is passed from the first section to the second section and fed to the second section with a substantially constant weight per unit length.

6. A picker having the construction defined in claim 5, together with means for moving the surface of the support engaged by the lap forward with the lap.

7. A picker having the construction defined in claim 5, together with means for moving the surface of the support engaged by the lap forward therewith at the same surface speed as that of the means for feeding the lap from the first section.

8. A picker comprising two-sections, means for feeding the lap from the first section, means for feeding the lap to the second section, an evener mechanism for the latter feeding means, a pair of vertically spaced

rolls extending across and beneath the lap between the two feeding means, an endless apron on said rolls and means for bodily raising and lowering said rolls and apron in coordination with each decrease and increase in the speed of the means for feeding the lap to the second section.

9. A picker having the construction de-

fined in claim 8, together with means for driving one of said rolls acting to move the apron forward with the lap at the same surface speed as that of the means for feeding the lap from the first section. 10

In testimony whereof, I have signed my name to this specification.

HENRY J. MONTY.
